UNITED STATES PATENT OFFICE.

ARTHUR L. BEHNER AND JAMES SCOTT, OF CLEVELAND, OHIO.

CONVERTIBLE TROLLEY.

1,083,049.

Specification of Letters Patent. Patented Dec. 30, 1913.

Application filed May 31, 1912. Serial No. 700,556.

To all whom it may concern:

Be it known that we, ARTHUR L. BEHNER and JAMES SCOTT, citizens of the United States, residing at Cleveland, in the county 5 of Cuyahoga and State of Ohio, have invented certain new and useful Improvements in Convertible Trolleys, of which the following is a specification.

Our invention has reference to a convertible 10 trolley in which two wheels are mounted tandem on a balancing frame in the harp and one or the other set of wheels is used according to the work to be done, all substantially as shown and described and particularly pointed out in the claims.

In the accompanying drawings, Figure 1 is a plan view of the invention in one of its working combinations and Fig. 2 is an elevation thereof. Fig. 3 is a sectional plan view of the invention in a different combination from Fig. 1 as hereinafter described, and Fig. 4 is a side sectional elevation of Fig. 3.

The trolley construction as thus shown is 25 essentially of the convertible type, the idea being in one case to have a pilot wheel which will run in advance of the trolley wheel proper and cut away accumulated ice on the wire, and in the other case to 30 substitute the said ice cutting wheel, when not needed, with a contact or current conveying wheel but retaining the same rear or real trolley wheel as in the first shown combination.

In the combination of parts shown in 35 Figs. 1 and 2 the construction comprises a suitably shaped harp H, an equalizing or balancing frame F pivotally mounted near its middle on a spindle or shaft S which it- 40 self is removably fixed in the top of the harp in the place of the usual trolley shaft in that position. The respective and differ- 45 ent wheels 2, 3 and 4, are mounted in the said frame F on front and rear shafts 5 and 6 respectively, and which are remov- 50 ably fixed in the frame F by cotter pins 7 or their equivalent. The plan of the invention contemplates the easy exchange of the distinctly ice cutting wheel or device 2 and the front wheel 4 shown in Figs. 3 and 4 according to the needs of the service. If, 55 for instance, it be found that the weather conditions are such as to threaten or to have

actually produced an accumulation of ice 55 on the line wire the conducting wheel 4 is removed and the ice cutter 2 substituted therefor. Then as soon as the trouble has been remedied, the ice cutter can be removed and the conducting wheel 4 substituted in its place. The latter arrangement 60 may be considered as the normal one, and is always used when a track clearing wheel like the ice cutter 2, or its equivalent, is not required. As to the said wheel 2 itself 65 as an article, it will be seen that it has the usual V-shaped peripheral channel of a common form of trolley wheel to run on the wire w, and a series of transverse holes h through the base of said channel or groove 70 from side to side which produce sharp cutting edges and are adapted to literally cut the ice from the wire. The said holes are near enough together to practically cut the ice from one to the other on the wire. A lubricating cavity 10 is provided within the 75 hub of the wheel which may be packed with wool waste or other suitable packing, and metallic bushings 12 and insulating bushings 13 therefor are carried by the shaft 5. These latter bushings of course insulate the 80 said wheel from the electric current and confine it to the single function of removing the ice from the trolley wire. But ice storms are usually of short duration how- 85 ever severe and trying they may be to the line while they continue, and when the said wheel 2 has served its purpose it is ex- 90 changed for the wheel 4 shown in Figs. 3 and 4 and which is designed to be elec- 95 trically active with wheel 3, as one of the conducting members of the combination.

The rear wheel 3 is of a roller pattern 100 preferably rather than having the compara- tively deep and narrow channel of the usual single trolley wheel and of which the wheel 95 4 may be considered a good example. The wide and slightly concave surface of the said wheel provides a wide lateral tread or bearing for travel on the wire w and across frogs in the line and accommodates the 100 wheel to curves or bends which are faithfully followed by the wheel 4 in advance. We might of course employ a wheel with less breadth of bearing or with a more de- 105 cidedly grooved or channeled bearing sur- face but the form shown readily lends itself

to any devious or sinuous portions of the line and holds a good working contact across all webs or connections between wires as they are found in overhead systems. The 5 said rear wheel 3 is the same in any case or whatever front wheel may be used, and is supported in the rear and wider portion of the equalizing frame F on a shaft 6, which has a perforated tubular bushing 16 10 fixed firmly in the ends of said wheel and exposed to the lubricating cavity 18 therein as seen in Fig. 3. The immediate ends of the said wheel are sealed fluid tight about the tubular sleeve 16 so as to prevent escape 15 of oil to the spring conducting contacts 20 at said ends, and the wheel has its bearing between said sleeve and the shaft while the shaft is removably fixed in the said frame.

The wheel 4 is provided with metallic 20 bushings 22 like the bushings 12 of the ice cutting wheel 2, but not the insulating bushings 13, and has spring contacts 23 like the corresponding contacts 20 for wheel or roller 3.

25 Structurally the balancing frame F is shown as curved downwardly at its front where it is adapted to play between the two stops 24 and 25 on the frame F, as seen in Fig. 4, and limit the tilting of the said frame 30 on its pivot, the excess of weight being at the front of the pivot with the natural tendency to tilt down at the front and hold the trolley wheel 3 up in contact at all times. Normally the parts will sustain relations 35 about as seen in Figs. 3 and 4, and any deviation from this position will depend on the elevation of the line wire as compared with the top of the car. The limit of reach, high or low, is within the play between the 40 stops 24 and 25. We might of course supplement the gravity of said frame with a spring but find that it is not really needed to maintain a good working relation under all usual or even abnormal conditions.

45 The wire w is referred to as the trolley wire or track, and by removing the insulating bushings 13 the bushings 12 can be moved up in wheel 4 and make room for the contact springs 22, so that the said bushings 50 12 and shaft 14 serve for both the said wheels 2 and 4.

If the ice cutting wheel or its equivalent were made stationary instead of rotating so as to cut the ice by a scraping action it would 55 still serve our purpose and be within the spirit of our invention and the said wheel or part would run upon and be guided by the wire substantially after the manner now shown.

60 If preferred, the wheel 4 could run as an idler for the reason that the trolley wheel 2 serves to make the necessary running contacts, but for obvious reasons we prefer to make said wheel of service beyond merely

serving as a balancing medium on the frame 65 F. In fact we deem it of the highest possible advantage to have a double trolley bearing on or in contact with the line wire, especially in high speed service, for the reason that it reduces jumping of the trolley on the 70 wire. Heretofore with a single wheel and with high speed on an interurban road particularly where the conditions are not the most favorable for rapid travel there has been constant danger of the trolley making 75 skips on the wire which imparts severe shocks to the system as well as causing severe sparking and injury to the apparatus. But by having two contact wheels at work at the same time we completely eliminate the dangers attending a single contact. When the trolley is placed upon the wire the rear wheel is tilted up and the first to make contact and it then instantly throws the wheel 80 up also. 85

What we claim is:

1. A trolley comprising a harp having integral cross-bars front and rear in its lower portion between its sides, in combination with a balancing frame pivoted in the top of 90 said harp having its greater weight forward of said pivot and confined at its front end in the space between said cross-bars between which it has play, a trolley wheel mounted in the rear of said frame behind said pivot 95 and a front wheel in said frame in front of said pivot and adapted to run in advance of said trolley wheel, the said balancing frame having its front portion curved downward at substantially right angles to the 100 body thereof and substantially on the radius of said front wheel, whereby a cross wire struck by the downward portion of said frame will be directed upward onto said wheel and breakage of the wire avoided. 105

2. A harp for a trolley having an equalizing frame pivotally mounted in its top and curved downwardly at its front end at substantially right angles between the sides of the harp, said harp having front and rear 110 stops between its sides intermediate its upper and lower ends between which the curved end of said frame is confined and has a limited swinging movement, in combination with two wheels mounted tandem in said 115 frame at substantially equal distances from the pivot thereof on the harp, the front wheel serving as a pilot and the rear wheel having a substantially barrel shape with a concave bearing surface running transversely of the direction of travel and substantially the full width of the said harp 120 at its rear and having electrical connections at its ends.

3. A harp for a trolley having a transversely disposed shaft in the top thereof, an equalizing frame pivoted on said shaft and having wheels mounted therein front and

rear of said pivot respectively, said frame curved downwardly at its front between the sides of the harp and cross pieces on the inside of said harp between the sides thereof
5 within which the end of the frame is adapted to play and limit the pivotal movement of the frame.

In testimony whereof we affix our signatures in presence of two witnesses.

ARTHUR L. BEHNER.

JAMES SCOTT.
